BENJAMIN C. WEBSTER, OF BRIDGEPORT, CONNECTICUT, ASSIGNOR TO HARVEY HUBBELL, INCORPORATED, OF BRIDGEPORT, CONNECTICUT, A CORPORATION OF CONNECTICUT.

SWITCH MOVEMENT.

1,149,312.

Specification of Letters Patent. Patented Aug. 10, 1915.

Application filed September 8, 1914. Serial No. 860,764.

To all whom it may concern:

Be it known that I, BENJAMIN C. WEBSTER, a citizen of the United States, residing at Bridgeport, county of Fairfield, State of Connecticut, have invented an Improvement 5 in Switch Movements, of which the following is a specification.

This invention has for its object to provide a simple and inexpensive reversible 10 switch movement of large current carrying capacity which will occupy but little space, will make and break quickly and will be equally adapted for key sockets and snap switches.

15 With these and other objects in view I have devised the novel switch mechanism of which the following description in connection with the accompanying drawing is a specification, reference characters being 20 used to indicate the several parts.

Figure 1 is a plan view on a greatly enlarged scale of the lower insulating block and the parts carried thereby; Fig. 2 a view partly in vertical section and partly in elevation illustrating my novel switch mechanism as applied to a key socket; Fig. 3 a 25 section on the line 3—3 in Fig. 1, looking in the direction of the arrows; Fig. 4 a perspective view of the body of the contact member detached; Fig. 5 a view of the contact member complete; Fig. 6 a detail view partly in elevation and partly in section of the switch mechanism detached, the position 30 of the parts corresponding with Fig. 1; Fig. 35 7 a section on the line 7—7 in Fig. 6, looking in the direction of the arrows, showing a position of the parts in winding the tension spring; Fig. 8 a detail view of the cam and shaft detached; and Fig. 9 is a view corresponding with Fig. 6 showing the position 40 of the parts an instant before the snap movement of the contact member takes place.

10 denotes the upper insulating block and 11 the lower insulating block by which the 45 operative parts are carried, said blocks being provided with recesses which receive the parts, leaving them wholly inclosed.

12 denotes the carrying bracket which is secured to the lower insulating block by a 50 screw 13 and in which the shaft 14 is mounted to rotate.

15 denotes a cam which is carried by the shaft and is provided with high points 16 diametrically opposite to each other and 55 with low points 17 diametrically opposite

to each other and mid-way between the high points leaving inclines 18 between the high points and the low points. The cam has formed integral therewith or rigidly secured there to a bar 19 which lies parallel with 60 the shaft and is provided with an eye 20 through which the shaft passes. The shaft is shown as provided with flat sides, indicated by 21, and the cam and eye are provided with correspondingly shaped openings which receive the shaft but retain the cam and eye against rotary movement independently of the shaft.

22 denotes the contact member as a whole which has rotary movement on the shaft 70 independently thereof. This member comprises a bar 23 having a slot 24 and arms 25 and 26, each having a hole which receives the shaft freely.

27 denotes the contact plates which lie on 75 opposite sides of arm 26 and are each provided with inwardly turned lips 28 which engage the arm and act to retain the plates against rotary movement independently of the arm. The arm and contact plates are 80 provided with alined slots indicated by 29, the purpose of which will presently be explained.

30 denotes the detent member as a whole which has both rotary and longitudinal 85 movement on the shaft and independently thereof. This member comprises a plate 31 having a hole through which the shaft passes, permitting said member to slide freely on the shaft, an arm 35 adapted to 90 engage and slide in slot 24 in bar 23 of the contact member, and an arm 36 adapted to engage and slide in alined slots 29 in arm 26 of the contact member and in the contact plates, and to engage one of the openings in 95 the carrying bracket to lock the contact member in either the circuit opening or circuit closing position. The engagement of arm 35 with the seat in bar 23 transmits the rotary movement of the contact member to 100 the detent member. Plate 31 of the detent member is shaped to correspond with the cam, that is, it is provided with high points diametrically opposite to each other and with low points diametrically opposite to 105 each other and midway between the high points, leaving inclines between the high points and low points and normally opposed to the inclines 18 of the cam. The high points and the low points of the detent mem- 110

ber and the cam are adapted to interlock in their normal or inoperative position, as shown in Fig. 6, and in operation the high points of the cam force the detent member 5 longitudinally on the shaft to cause the release of the contact member as shown in Fig. 9 and as will be more fully explained. A spring 37 bearing against arm 25 of the contact member and against plate 31 of the 10 detent member acts to normally retain the detent member in the locking position.

38 denotes a tension spring coiled about the shaft and having arms 40 which are adapted respectively to engage bar 23 of the 15 contact member and to be engaged by bar 19 of the cam.

41 and 42 denote the terminals. It of course makes no difference which way the current passes. Suppose, for example, that 20 the current enters at terminal 41, passes to the screw shell indicated by 43, thence through the lamp, (not shown), from which it passes to center contact 44, thence through a screw 45 to a contact blade 46 25 which extends into position to be engaged by the contact plates of the contact member. From the contact member the current passes to a contact blade 47. This contact blade and terminal 42 extend from a plate 48 30 which is secured to the lower insulating block by a screw 49.

Carrying bracket 12 is provided with four openings 50, equidistant from the shaft, either of which is adapted to be engaged by 35 arm 36 of the detent member to lock the contact member either in engagement or out of engagement with the contact blades.

The operation is as follows: Starting with the parts locked in the circuit opening position, as in Figs. 1, 2, 3 and 6, a quarter turn 40 of the shaft in either direction will cause the cam to move the detent member longitudinally on the shaft against the power of spring 37 from the position shown in Fig. 6 45 toward the position shown in Fig. 9, and will cause bar 19 which extends from the cam, through engagement with one of the arms of the tension spring, to wind said spring, as clearly shown in Fig. 7, this winding movement continuing, until the parts 50 are in the position shown in Fig. 9 that is arm 36 of the detent member has been moved entirely out of engagement with the opening 55 50 in the carrying bracket with which it has been in engagement, when the other arm of the tension spring, which is in engagement with bar 22 of the contact member will impart a quarter turn to the contact member with a snap and will place the contact plates 60 in engagement with the contact blades. As soon as the snap movement of the contact member takes place, spring 37 will return the detent member to its normal or locking position, as in Fig. 6, in which arm 36 of the 65 detent member will pass into one of the

openings 50 in the carrying bracket and lock the contact member in place until it is again released by a quarter turn of the shaft and cam. Briefly then, starting with the contact member in the position shown, 70 the first quarter turn of the shaft and cam in either direction will close the circuit, the second quarter turn will open it again, the third quarter turn will close it again and the fourth quarter turn will open it again, leaving the parts in the starting position. 75

Having thus described my invention I claim:

1. A mechanism of the character described comprising a rotatable contact member having a bar, a rotatable cam having high points and inclines and having a bar extending therefrom, a longitudinally movable detent member having a plate provided with high points and inclines coöperating with those 85 on the cam, and a tension spring having arms engaging the bars of the contact member and the cam, rotation of the cam causing the detent member to release the contact member, and the bar of the cam acting to 90 wind the spring and said spring acting on the bar of the contact member to rotate said member when released.

2. A mechanism of the character described comprising a shaft, a contact member rotatable thereon and having a bar, a cam rotating with the shaft and having a bar, and high points, a detent member rotatable and longitudinally movable on the shaft and having a plate with high points coöperating 100 with those on the cam, and a tension spring having arms engaging the bars of the contact member and the cam.

3. A mechanism of the character described comprising a shaft, a contact member rotatable thereon and having a bar, a cam carried by the shaft and having a bar, a detent member rotatable and longitudinally movable on the shaft, said cam and detent member having coöperating high points and 105 inclines, a tension spring carried by the shaft and having arms engaging the bars and a spring acting to move the detent member longitudinally.

4. A mechanism of the character described comprising a shaft, a contact member rotatable thereon and having a bar provided with a slot, a cam carried by the shaft and having a bar and a high point, a detent member rotatable and longitudinally movable on the shaft and having a high point coöperating with the cam, an arm engaging the slot in the contact member and a locking arm, and a tension spring having arms engaging the bars of the contact member and 115 the cam.

5. A mechanism of the character described comprising a shaft, a bracket in which the shaft is journaled and which is provided with locking openings, a contact member 130

- rotatable on the shaft and having a slotted bar, a cam carried by the shaft and having a bar, a detent member rotatable and longitudinally movable on the shaft, said cam and 5 detent member having interengaging points and said detent member having an arm engaging the slot in the contact member and a locking arm adapted to engage either opening in the bracket and a tension spring having arms engaging the bars of the contact member and the cam.
6. A mechanism of the character described comprising a shaft, a bracket in which the shaft is journaled and which is provided 10 with locking openings, a contact member rotatable on the shaft and having a slotted bar, a cam carried by the shaft and having a bar, a detent member rotatable and longitudinally movable on the shaft, said cam 15 and detent member having interengaging points and said detent member having an arm engaging the slot in the contact member and a locking arm engaging the contact member and a locking arm engaging the contact member and adapted to engage either opening in the bracket, a tension spring having arms engaging the bars of the contact member and the cam and a spring acting to 20 return the detent member to the locking position after it has been actuated by the cam.
7. A mechanism of the character described comprising a shaft rotatable in either direction, a contact member rotatable on the shaft, a cam fixed to the shaft, a detent member 25 rotatable and longitudinally movable on the shaft, said detent member and cam having interengaging points and a tension spring engaging both the contact member and the cam.
8. A mechanism of the character described comprising a shaft, a contact member rotatable thereon a detent member rotatable and longitudinally movable on the shaft, a cam fixed to the shaft and a tension spring 30 engaging both the contact member and the cam, said cam and detent member being provided with high and low points and opposed inclines, substantially as described, for the purpose specified.
9. A mechanism of the character described comprising a shaft, a contact member rotatable thereon and having a bar, a cam carried by the shaft and having a bar, a detent member rotatable and longitudinally 35 movable on the shaft, said cam and detent member having corresponding high and low points and opposed inclines and a tension spring coiled about the shaft and having arms engaging both sides of both bars so that when the shaft is rotated the bar of the cam will wind the spring.
10. A mechanism of the character described comprising a bracket having locking openings, a shaft rotatable in said bracket, 40 a contact member rotatable on the shaft and having a bar, a cam rotating with the shaft and having a bar, a detent member rotatable and longitudinally movable on the shaft and having an arm engaging the contact member and adapted to engage an opening in the bracket, and a tension spring having arms engaging opposite sides of the bars, said detent member being moved longitudinally by the cam to release the contact member, the bar of the cam acting on one arm of the spring to wind said spring, and the other arm of the spring actuating the contact member when released by the detent member.
11. In a mechanism of the character described the combination with contact blades and a rotatable contact member having plates adapted to engage the blades, of a shaft on which the contact member has rotary movement, a cam rotating with the shaft, a detent member rotatable and longitudinally movable on the shafts, said cam and detent member having coöperating high points and opposed inclines, and a tension spring having arms oppositely engaging both the contact member and the cam.
12. In a mechanism of the character described the combination with contact blades and rotatable contact member having plates adapted to engage the blades and a bar, of a shaft on which the contact member has rotary movement, a cam rotating with the shaft and having a bar, a detent member rotatable and longitudinally movable on the shaft, said cam and detent member having coöperating high points and a tension spring having arms engaging the opposite sides of the bars.
13. In a mechanism of the character described the combination with contact blades, a contact member comprising a slotted bar, arms, and contact plates carried by one of the arms, of a shaft on which the contact member has rotary movement, a cam rotating with the shaft and having a bar, a detent member rotatable and longitudinally movable on the shaft, said cam and detent member having coöperating high points and said detent member having an arm engaging the slot and an arm for locking the contact member, and a tension spring having arms engaging opposite sides of the bars.
14. In a mechanism of the character described the combination with a carrying bracket having locking openings, a contact member comprising a bar having a slot, arms, and contact plates carried by one of the arms, of a shaft on which the contact member has rotary movement, a cam rotating with the shaft and having a bar, a detent member rotatable and longitudinally movable on the shaft, said cam and detent member having coöperating high points and said detent member having an arm engaging the slot and an arm engaging the lock-

ing member and adapted to engage either opening in the bracket and a tension spring having arms engaging opposite sides of the bars.

- 5 15. In a mechanism of the character described the combination with a rotatable contact member having a bar and a shaft on which said member has rotary movement, of a cam rotating with the shaft, a detent member rotatable and longitudinally movable on the shaft and having a bar, said

cam and detent member having coöperating high points, a tension spring having arms engaging opposite sides of the bars and a spring bearing on the contact member and 15 the detent member.

In testimony whereof I affix my signature in presence of two witnesses.
